(57) **CLAIM**

I claim the ornamental design for a "gaming machine," as shown and described.

DESCRIPTION

FIG. 1 is an isometric view of a gaming machine.

FIG. 2 is a left view of the gaming machine shown in FIG. 1. FIG. 3 is a front view of the gaming machine shown in FIG. 1. FIG. 4 is a right view of the gaming machine shown in FIG. 1. FIG. 5 is a top view of the gaming machine shown in FIG. 1; and,

FIG. 6 is an enlarged view of a button area shown in FIG. 1. The broken lines are only for illustrative purposes to show visible environmental structure and form no part of the claimed design.

1 Claim, 3 Drawing Sheets# US D691,665 S
